(57) **CLAIM**

The ornamental design for a mobile pneumatic therapy system as shown and described.

DESCRIPTION

FIG. 1 is a top front perspective view of a mobile pneumatic therapy system;

FIG. 2 is a front view of the mobile pneumatic therapy system;

FIG. 3 is a rear view of the mobile pneumatic therapy system;

FIG. 4 is a right side view of the mobile pneumatic therapy system;

FIG. 5 is a left side view of the mobile pneumatic therapy system;

FIG. 6 is a top view of the mobile pneumatic therapy system;

FIG. 7 is a bottom view of the mobile pneumatic therapy system; and,

FIG. 8 is a top rear perspective view of the mobile pneumatic therapy system in a folded configuration.

The dash dash broken lines show portions of the mobile pneumatic therapy system that form no part of the claimed design.

1 Claim, 8 Drawing Sheets
